(57) **CLAIM**

The ornamental design for a digital badge, as shown and described.

DESCRIPTION

FIG. 1 is a front perspective view of a digital badge showing my new design with a strap.

FIG. 2 is a front view of the digital badge of FIG. 1 shown without the strap.

FIG. 3 is a back view thereof.

FIG. 4 is a left side view thereof.

FIG. 5 is a right side view thereof.

FIG. 6 is a top view thereof.

FIG. 7 is a bottom view thereof; and,

FIG. 8 is a back perspective view of the digital badge of FIG. 1.

The broken lines showing a strap in FIGS. 1 and 8 depict environmental structure that forms no part of the claimed design.

1 Claim, 6 Drawing Sheets(56)
